UNITED STATES PATENT OFFICE.

WILLIAM BARNUM COWLES, OF CLEVELAND, OHIO.

AIR COMPRESSOR AND INTERCOOLER.

SPECIFICATION forming part of Letters Patent No. 699,288, dated May 6, 1902.

Application filed August 16, 1901. Serial No. 72,529. (No model.)

To all whom it may concern:

Be it known that I, WILLIAM BARNUM COWLES, a citizen of the United States, residing at Cleveland, in the county of Cuyahoga and State of Ohio, have invented certain new and useful Improvements in Air Compressors and Intercoolers; and I do hereby declare the following to be a full, clear, and exact description of the invention, such as will enable others skilled in the art to which it app pertains to make and use the same.

My invention relates to what is termed by me an "air compressor and intercooler" or an improved apparatus in which the air is compressed into reservoirs under high pressure and the heat given out by the air in process of compression is used to warm that part of the compressed air taken from said reservoirs which is supplied at a lower pressure and after expansion to apparatus to be operated by the said reduced pressure.

My invention is especially intended for use in connection with the apparatus devised by me and used in the United States Navy for closing bulkhead-doors and hatches on board ship, in which compressed air is stored up at high pressure in strong flasks and is then supplied at a reduced pressure to the mechanism for operating the doors or hatches.

My invention will be understood by reference to the accompanying drawings, in which the same parts are indicated by the same letters throughout the views.

Figure 1 is a plan view of the apparatus; and Fig. 2 is a diagram, partly in elevation and partly in section.

A, A', and A² are the three cylinders arranged in series to compress the air in three steps. The largest cylinder A draws in air from the atmosphere through the inlet A⁰ and forces the same into the pipe B, whence it enters the coil C in the tank G. From this coil the partly-compressed air returns through the pipe B' to the cylinder A', where after being further compressed it is delivered to the pipe B² and from it to the coil C'. Passing from this coil it enters the pipe B³, by which it is carried back to the cylinder A², where the final compression takes place, and the compressed air is carried by the pipe B⁴ to the coil C², whence it is delivered by the pipe B⁵ to the pipe B⁶, opening into the air-flask D.

It will be seen that the cylinders A, A', and A² and the pipes leading therefrom and also the coils C, C', and C² are graded in size to correspond to the decrease of volume of the air due to the compression.

E and E' are two reducing-valves in the path of the air under pressure from the pipe B⁶ to the supply-pipe F, which supply-pipe opens into the large coil H, connected to the air-pressure main K. Under the ordinary working pressure air passes through the two reducing-valves E and E', entering the pipe F and passing to the fluid-pressure main K; but in order to provide for the admission of air to the air-pressure main at an increased or emergency pressure I provide a by-pass pipe N, which is opened by the valve M, controlled by the emergency-lever m, so that when this valve M is opened the compressed air from the pipe B⁶ passes through the reducing-valve E only, then goes through the by-pass instead of the second reducing-valve E', so that by simply turning the hand-lever m the emergency pressure is applied to the air-pressure main K.

O, O', and O² are pressure-gages which show the pressure in the air-flask D, the emergency pressure, and the ordinary working pressure, respectively.

The tank G is kept supplied with water in circulation by means of the pump Q, operated by the piston-rod q, which pump draws water through the pipe p' from the tank P and delivers it through the pipe R to the water-jackets surrounding the cylinders A, A', and A², from whence it passes through the pipe S and enters the bottom of the tank G. As soon as this water rises above the mouth p⁰ of the pipe p it is siphoned into the tank P, so that the water circulates from said tank P around the cylinders A, A', and A² into the tank G and around the coils contained therein and is finally drawn off from the top of said tank, returning to the tank P. Any loss of water due to the leakage, evaporation, &c., may be supplied to the tank P in any convenient way; but this loss will ordinarily be very small.

The flasks D are ordinarily mounted in supports X, secured to any convenient bulkhead Y.

It will be seen that the air from the com-

pressor-cylinder A is cooled in the tank G before entering the cylinder A', where it is heated again by compression, and that this further compressed air is again cooled in the tank G before passing to the cylinder A², where it is again compressed and incidentally reheated, whence it passes through the tank H to be again cooled before being delivered to the flask D. The heating up of the air incidental to compression is obviated in a measure only by the water-jackets surrounding the cylinders A, A', and A². On the other hand, the compressed air passing to the pipe F on its way to the fluid-pressure main is incidentally cooled as it expands, and this, entering the coil H, is heated up by the water in the tank G, so that it finally reaches the fluid-pressure main K at a moderate temperature. Thus it will be seen that in the same tank G the air being compressed is cooled and the air being expanded is warmed, the heat incident to compression being used to neutralize the loss of heat incident to expansion.

By the use of the apparatus as herein described an exceedingly compact arrangement is secured in which only a small volume of circulating water is required. This is particularly important on board ship, where it is desirable to cut down the weights as much as possible and at the same time to save as much space as practicable. Moreover, the small quantity of water required will render it practicable to use fresh water for the circulating system, thus preventing the corrosive effects of salt water ordinarily used on ocean-steamers for like purposes.

The number of the compressor-cylinders and corresponding coils in the tank G may be varied at will, as also may the number of flasks D and the number and arrangement of reducing-valves E and E'. Moreover, various other changes might be made in the herein-described apparatus and in the details thereof which could be used without departing from the spirit of my invention.

Having thus described my invention, what I claim, and desire to secure by Letters Patent of the United States, is—

1. In an apparatus of the character described, the combination of a heating and cooling tank, a reservoir for compressed air, means for supplying compressed air to said reservoir including a cooling-coil in said tank, and means for carrying off air from said reservoir at a reduced pressure including a heating-coil in said tank, substantially as described.

2. In an apparatus of the character described, the combination of a heating and cooling tank, a reservoir for compressed air, means for supplying compressed air to said reservoir including a cooling-coil in said tank, and means for carrying off air from said reservoir including one or more reducing-valves, and a heating-coil, beyond said reducing valve or valves, located in said tank and connected to

the fluid-pressure main, substantially as described.

3. In an apparatus of the character described, the combination of a heating and cooling tank, a reservoir for compressed air, means for supplying compressed air to said reservoir including a cooling-coil in said tank, means for carrying off said compressed air, including two reducing-valves, a by-pass for one of said reducing-valves, means for controlling said by-pass by hand, a heating-coil located in said tank, and a fluid-pressure main receiving the air from said heating-coil, substantially as described.

4. In an apparatus of the character described, the combination of a tank and means for circulating water therethrough, of a reservoir for compressed air, means for supplying compressed air to said reservoir including a cooling-coil in said tank, and means for carrying off air from said reservoir at a reduced pressure including a heating-coil in said tank, substantially as described.

5. In an apparatus of the character described, the combination of a tank and means for circulating water therethrough, of a reservoir for compressed air, means for supplying compressed air to said reservoir including a cooling-coil in said tank, and means for carrying off air from said reservoir including one or more reducing-valves, and a heating-coil, beyond said reducing valve or valves, located in said tank and connected to the fluid-pressure main, substantially as described.

6. In an apparatus of the character described, the combination of a tank and means for circulating water therethrough, of a reservoir for compressed air, means for supplying compressed air to said reservoir including a cooling-coil in said tank, means for carrying off said compressed air, including two reducing-valves, a by-pass for one of said reducing-valves, means for controlling said by-pass by hand, a heating-coil located in said tank, and a fluid-pressure main receiving the air from said heating-coil, substantially as described.

7. In an apparatus of the character described, the combination of a heating and cooling tank, a reservoir for compressed air, means for supplying compressed air to said reservoir comprising a compressor-cylinder with a water-jacket therefor, a cooling-coil in said tank, means for carrying off air from said reservoir at a reduced pressure including a heating-coil in said tank, and means for circulating water through said tank and said jacket, substantially as described.

8. In an apparatus of the character described, the combination of a tank, a reservoir for compressed air, and a fluid-pressure main, means for supplying compressed air to said reservoir comprising a compressor-cylinder with a water-jacket therefor, a cooling-coil in said tank, means for carrying off air from said reservoir including one or more reduc-

ing-valves, and a heating-coil located in said tank and connected to said reservoir and to the fluid-pressure main, and means for circulating water through said tank and said jacket, substantially as described.

9. In an apparatus of the character described, the combination of a tank, a reservoir for compressed air, means for supplying compressed air to said reservoir including a compressor-cylinder with a water-jacket, a cooling-coil in said tank, and means for carrying off said compressed air comprising a pipe, two reducing-valves in said pipe, a bypass for one of said reducing-valves, means for controlling said by-pass by hand, a heating-coil located in said tank, a fluid-pressure main receiving air from said heating-coil, and means for circulating water through said tank and said jacket, substantially as described.

10. In an apparatus of the character described, the combination of a tank and means for circulating water therethrough, of a reservoir for compressed air, means for supplying compressed air to said reservoir comprising a plurality of air-compressor cylinders, a plurality of cooling-coils in said tank, and means for carrying off air from said reservoir at a reduced pressure including a heating-coil in said tank, substantially as described.

11. In an apparatus of the character described, the combination of a tank and means for circulating water therethrough, of a reservoir for compressed air, means for supplying compressed air to said reservoir comprising a plurality of air-compressor cylinders, a plurality of cooling-coils in said tank, and means for carrying off air from said reservoir including one or more reducing-valves, and a heating-coil located in said tank and connected to the fluid-pressure main, substantially as described.

12. In an apparatus of the character described, the combination of a tank, and means

for circulating water therethrough, of a reservoir for compressed air, means for supplying compressed air to said reservoir comprising a plurality of air-compressor cylinders, a plurality of cooling-coils in said tank, means for carrying off said compressed air, including two reducing-valves, a by-pass for one of said reducing-valves, means for controlling said by-pass by hand, a heating-coil located in said tank, and a fluid-pressure main receiving the air from said heating-coil, substantially as described.

13. In an apparatus of the character described, the combination of a tank, a reservoir for compressed air, means for supplying compressed air to said reservoir comprising a plurality of compressor-cylinders with water-jackets therefor, and cooling-coils in said tank connected to said cylinders, means for carrying off air from said reservoir at a reduced pressure including a heating-coil in said tank, and means for circulating water through said tank and said jackets, substantially as described.

14. In an apparatus of the character described, the combination of a tank, a reservoir for compressed air, means for supplying compressed air to said reservoir comprising a plurality of compressor-cylinders with water-jackets therefor, and cooling-coils in said tank connected to said cylinders, means for carrying off air from said reservoir including one or more reducing-valves, and a heating-coil located in said tank and connected to the fluid-pressure main, and means for circulating water through said tank and said jacket, substantially as described.

In testimony whereof I affix my signature in presence of two witnesses.

WILLIAM BARNUM COWLES.
